UNITED STATES PATENT OFFICE.

JOHN W. BROWN AND ALBERT A. GEHRT, OF QUINCY, ILLINOIS, ASSIGNORS
TO THE COLLINS PLOW COMPANY, OF SAME PLACE.

BALING-PRESS.

SPECIFICATION forming part of Letters Patent No. 434,762, dated August 19, 1890.

Application filed December 16, 1889. Serial No. 333,992. (No model.)

To all whom it may concern:

Be it known that we, JOHN W. BROWN and ALBERT A. GEHRT, both of Quincy, in the county of Adams and State of Illinois, have 5 invented a certain new and useful Improvement in Baling-Presses, of which the following is a full, clear, and exact description, reference being had to the accompanying drawings, forming part of this specification.

10 Our invention relates to certain improvements in presses for baling hay, straw, excelsior, &c.; and our invention consists in features of novelty hereinafter fully described, and pointed out in the claims.

15 The object of our invention is to construct an inexpensive and effective power device for baling-presses.

Figure I is a top or plan view illustrative of our invention. Fig. II is a similar view 20 showing the parts in the position they occupy when the traverser has been forced to its forward position, the parts being shown in Fig. I in the position they occupy when the traverser is in its outer position. Fig. III is a 25 side elevation illustrating the parts in the position shown in Fig. II. Fig. IV is a side elevation of the power-head or casting.

Referring to the drawings, 1 represents the lever or sweep of the press.

30 2 represents a sweep-head or casting having laterally-extending arms 3 and mounted loosely on a rod or shaft 4. On the outer ends of the arms 3 friction-rollers 5 are mounted. The sweep is united to the sweep-head by 35 means of bolts and nuts, as shown.

6 represents a power-head or casting mounted on a shaft or rod 7 at one side of the first-named shaft or rod.

8 represents a curved slot in the outer end 40 of the head or casting 6, in which fits a roller or pin 9, that connects the outer end of the pitman 10 to the head or casting 6. The pitman 10 is connected at its inner end to the plunger or follower (not shown) of the press.

45 The pitman is jointed at 11. The slot 8 is preferably made in the arc of a circle, as shown in Fig. I. The outer end of the pitman from the joint 11 to the roller or pin 9 is preferably made in two parts, as shown in 50 Fig. III, one part extending over the head 6 and the other under it.

12 represents the main ground sill, connecting the power to the baling portion of the press, as usual, and over which the animals step in their circuitous route or travel. The 55 pitman 10 moves over and in close proximity to the sill 12.

13 represents a curved rib or track on the inner end of the power-head or casting 6, and against which the rollers 5 alternately bear 60 as the lever or sweep moves around the circuit.

The operation is as follows: The sweep or lever being moved in the direction indicated by the arrow in Fig. I, one of the rollers 5 65 comes against the raised track or rib 13 and forces the power-head or casting around in the direction indicated by the arrow A, Fig. I. This causes the forward movement of the pitman (and consequently, of course, the forward movement of the traverser) until the parts reach the position shown in Fig. II. The roller 5 now leaves the raised track 13, and the power-head or casting with the pitman rebound back in the direction indicated by 70 the dotted arrow, Fig. II, to their original position, or that shown in Fig. I. The movement of the sweep or lever continuing brings the next roller 5 against the track 13, and the parts are again forced forward, two forward 75 movements of the pitman and traverser being thus obtained at each revolution of the sweep or lever. By using the slot 8 in the outer end of the power-head or casting the roller or pin 9 between the outer end of the pitman 80 and the head is permitted to approach the pivot of the power-head as the traverser moves forward and as the density of the material being pressed increases, thus converting speed into power. This is also facilitated by mounting the power-head and sweep-head on separate pivots. By providing the raised track 85 90 95 13 on the power-head the sweep or cross-head is allowed to engage the power-head and be disengaged therefrom without the point of bearing between the sweep-head and power-head traveling to the end of the latter, thus increasing the amount of travel of the traverser without decreasing the power of the press as when the power is required the point 100 of bearing between the outer end of the pitman and the power-head is very close to the

point of bearing between the sweep-head and the power-head, and in addition to this advantage, arising from the use of the raised track 13, there is that of being enabled to connect the pitman to the power in a much simpler and easier manner than can be obtained by making this connection with the pitman beneath the power-head, as is necessary where the point of bearing between the sweep-head and power-head travels to the end of the power-head.

We claim as our invention—

1. The combination of a pitman, a power-head having a curved slot at its outer end and a curved track at its inner end, a sweep having a cross-head engaging the track, separate pivots for the power-head and the cross-head,

and a pin working in the slot and by which the pitman is connected to the power-head, substantially as described.

2. The combination of a pitman, a power-head having a curved slot at its outer end and a curved track at its inner end, a sweep having a cross-head provided with rollers engaging said track, separate pivots for the power-head and the cross-head, and a pin working in the slot and by which the pitman is connected to the power-head, substantially as described.

JOHN W. BROWN.
ALBERT A. GEHRT.
